UNITED STATES PATENT OFFICE.

JOHN B. BIALEK, OF PITTSBURGH, PENNSYLVANIA, ASSIGNOR TO SLAVONIC EVANGELICAL UNION OF AMERICA, OF PITTSBURGH, PENNSYLVANIA.

DESIGN FOR AN EMBLEM.

49,048.

Specification for Design.

Patented May 16, 1916.

Application filed March 8, 1916. Serial No. 82,942. Term of patent 14 years.

To all whom it may concern:

Be it known that I, JOHN B. BIALEK, a citizen of the United States of America, residing at 1601 Beaver avenue, North Side, Pittsburgh, in the county of Allegheny and State of Pennsylvania, have invented a new, original, and ornamental Design for Emblems, of which the following is a specification, reference being had to the accompanying drawing, forming part thereof.

The figure is a plan view of an emblem, showing my new design.

I claim:—

The ornamental design for an emblem, as shown.

JOHN B. BIALEK.
